UNITED STATES PATENT OFFICE.

WILLIAM A. DOBLE AND LEOPOLD M. KARNASCH, OF SAN FRANCISCO, CALIFORNIA,
ASSIGNORS TO THE PELTON WATER WHEEL COMPANY, OF SAN FRANCISCO, CALI-
FORNIA, A CORPORATION OF CALIFORNIA.

HYDRAULIC MOTOR.

1,173,416.

Specification of Letters Patent.

Patented Feb. 29, 1916.

Application filed April 4, 1913. Serial No. 758,764.

To all whom it may concern:

Be it known that we, WILLIAM A. DOBLE, a citizen of the United States, and LEOPOLD M. KARNASCH, a subject of the Empire of 5 Germany, residents of the city and county of San Francisco and State of California, have invented certain new and useful Improvements in Hydraulic Motors, of which the following is a specification.

10 The invention relates to hydraulic motors and particularly to hydraulic motors which are driven by a jet of water.

The object of the invention is to provide a hydraulic motor having a high efficiency.

15 Another object of the invention is to provide a jet operated hydraulic motor which will operate at a high efficiency at such speeds in relation to the speed of the jet, at which the heretofore constructed jet operated motors would operate at a low efficiency.

20 A further object of the invention is to provide a jet operated hydraulic motor which is capable of operation at a high efficiency at speeds ranging from approximately 50 per cent. of the velocity of the jet to 130 per cent. of the velocity of the jet and higher.

25 A further object of the invention is to provide a high speed hydraulic motor which is susceptible to very close regulation.

30 The invention possesses other advantageous features, which, with the foregoing, will be set forth at length in the following 35 description where we shall outline in full that form of the invention which has been selected for illustration in the drawings accompanying and forming part of the present specification. The novelty of the invention will be included in the claims succeeding said description.

35 From this it will be apparent that we do not limit ourselves to the showing made by such drawings and description, as we may 40 adopt many variations within the scope of our invention, as included in said claims.

45 Referring to said drawings: Figure 1 is a vertical section through one type of motor of our invention. Fig. 2 is a front view of 50 the motor, part thereof being shown in section. Fig. 3 is a detail showing in cross section the stationary splitter and several of the vanes; the vanes and splitter being curved to produce the maximum efficiency

when the vanes travel at 1.25 times the 55 velocity of the jet. Fig. 4 is a similar view showing the curvature of the splitter and vanes to produce a maximum efficiency when the vanes travel at .5 times the velocity of the jet. Fig. 5 is a side elevation, partly in 60 section, of the motor and nozzle, showing one means of regulating the speed of the motor. Fig. 6 is a side elevation, partly in section, of the motor and nozzle showing another means of regulating the speed of 65 the motor. Fig. 7 is a longitudinal horizontal section of one form of splitter, taken immediately below the upper flange. Fig. 8 is a cross section of one of the vanes of the runner, taken on the line A—A of Fig. 2. 70

In jet operated hydraulic motors, as heretofore constructed, and known generally as tangential water wheels or impact water wheels, the maximum efficiency of the motor is obtained when the speed of the center of 75 the buckets or the speed of revolution at the pitch circle is substantially one-half the speed of the jet. The pitch circle is a circle concentric with the wheel or runner and tangential to the axis of the jet. By reason 80 of this relation between the spouting velocity of the jet and the speed of the runner, such speeds have been fixed by the head of the water which is used. In the present construction the speed of the runners or 85 wheels is not directly dependent upon the spouting velocity of the jet, but the apparatus may be designed to operate at a high 90 efficiency at any speed, within certain limits, so that the speed of rotation of a given installation is not fixed by the available head of water. This is a great advantage in the 95 hydraulic generation of power, since it permits a much higher speed for a given head than has heretofore been practically and 100 economically possible. Theoretically, any speed relation between the jet and the runner may be obtained, but due to mechanical considerations, the most efficient speeds will fall within or substantially near the limits 105 hereinbefore set forth. Further, a jet of water traveling at a high speed is more readily controlled than a large body of water traveling at a slower speed, so that the present device, while embodying all of the advantages of hydraulic turbines in regard to speed and efficiency, has the further advantage of being readily governed or con-

trolled under varying loads. Apparatus of this description is generally used for driving electric generators, and in order that the voltage of the generated current be substantially constant under varying loads, it is advisable that the speed of the generator be substantially constant.

The apparatus consists of two revolving elements, mounted on the same shaft and spaced apart from each other, between which is arranged a normally stationary splitter for dividing the jet and directing the water at the proper angle into or against the vanes or buckets of the revolving elements.

The revolving elements, or runners 2, are preferably cast or fashioned separately and attached to a hub 3, which may be integral with the shaft 4 or may be bolted thereto. While we have stated that the rotating part of the apparatus comprises two revolving elements, it should be understood that these elements are securely fastened to each other, or to a common hub or shaft, or may be formed integral. The circumferential parts of the revolving elements or element are spaced apart from each other, producing in effect two revolving elements, and for the sake of convenience the rotating part will be so described, but it is to be understood that an integral structure having two circumferential portions or annular areas spaced apart falls within the meaning of the expression "two revolving elements." In Fig. 2 is shown an overhanging shaft construction in which the hub 3 is bolted to a flange on the shaft, but it is evident that the shaft may extend through the unit and be provided with a bearing on each side when desirable. The hub may be pressed on or keyed to the shaft and may be provided with two annular flanges, to which the runners may be attached.

Many variations in the method of mounting the runners are apparent, and it is our purpose to confine ourselves to no particular style or method of mounting.

Each runner consists preferably of an annular structure consisting of continuous inside and outside walls 5 and 6 between which are arranged a plurality of vanes 7, the number and spacing of which depends, among other factors, upon the power and speed of the runner. The vanes 7 are curved in the plane of the pitch line outward and backward toward the direction from which the jet is traveling, so that the reaction of the water in passing over the vanes will cause the runners to revolve. These vanes are curved in the plane of the pitch line at various curvatures, depending upon the desired speed of the runner in relation to the speed of the jet, as shown in Figs. 3 and 4. Since the various parts of each vane travel at different speeds, due to the distances of

such parts from the center of rotation, the curvature of the vanes vary from the inner to the outer ends thereof. That is, the curvature of the vane adjacent the inner wall 5, represented by line 75, Fig. 8, is sharper than the curvature of the vane adjacent the outer wall 6, represented by the line 76, the curvature flattening out somewhat from one to the other. The vanes may be either arranged radially or may be concave or convex in the vertical plane, depending, among other factors, upon the relative speed of the runner. In the drawings the vanes are shown convex, in order to facilitate the spreading of the water evenly over the entire surface thereof, but under conditions of operation it may be advisable to arrange the vanes radially or concave. The side walls 5 and 6 preferably diverge from each other, to increase the height and therefore the area of the vane outwardly, and the discharge edges 8 of the vanes are preferably curved outward to increase the discharge area.

Arranged between the runners, or between the annular projecting portions of the rotating element, preferably at a point below the axis of rotation, is a normally stationary splitter 9 mounted upon a suitable frame or support 12. The forward edge of the splitter intersects the axis of the jet 13, so that the water is equally divided thereby. The rear edges of the splitter lie close to the intake edges of the vanes, so that the water is projected from the splitter onto the vanes. The curvature of the splitter depends upon the curvature of the vanes, as shown in Figs. 3 and 4, and the curvature of the splitter above and below the axis of the jet, preferably varies in accordance with the curvature of the vanes above and below the pitch circle. In Fig. 7 we have shown a splitter in which the curvature varies from top to bottom. The greater curvature 9^a occurs at the upper portion of the splitter and the lesser curvature 9^b occurs at the lower portion of the splitter. The splitter is usually provided at its top and bottom edges with overhanging or projecting ribs or flanges 14 and the body of the splitter is curved out to meet these flanges.

Arranged between the two runners, at that part where the water is not entering or being discharged from the vanes, is a frame or structure 15 having closed side walls 16 lying adjacent the intake side of the vanes. This arrangement prevents the apparatus from operating as an air blower, decreases the windage losses, and consequently increases the efficiency of the apparatus. Surrounding the apparatus is a housing 19, which confines the water and also prevents windage losses. The apparatus is preferably arranged over a pit 21, the lower part of the apparatus lying below the top thereof,

so that the discharge water is readily collected and disposed of. The shaft is generally so placed that the water is discharged from the vanes before they rise above the side walls of the pit.

The jet of water 13 spouts from a nozzle 17 which is connected to the source of supply by a suitable pipe line. The size of the jet issuing from the nozzle may be controlled by a needle 18 which may be operated automatically or manually. On account of the size of the pipe line, however, and the velocity of the water traveling therein, it is not possible to vary the size of the jet 15 issuing from the nozzle by opening and closing the discharge aperture therein, to compensate for the varying load upon the hydraulic motor. The needle must be operated very slowly in order to prevent an excessive and destructive pressure at the lower 20 end of the pipe line, and other means must be employed for varying the energy delivered to the hydraulic motor. This may be accomplished in several ways, some of 25 which will be described herein.

In Fig. 5 is shown a means for diverting part or all of the jet from the splitter 9, by means of a jet deflector 22, the movement of which is controlled by the governor 23, 30 driven from the shaft 4, or other rotating part of the unit. The jet deflector 22 is mounted upon a suitably arranged rocker shaft 24 so that it may be moved about the axis of the shaft, and is connected to the governor 23 by the links and levers 35 25-26-27.

The governor operates, usually, to open and close valves in opposite sides of the cylinder 28, in which a piston connected to 40 link 27 is movable, to admit or discharge a fluid under pressure to or from the opposite sides of the piston. An increase in speed of the governor moves the jet deflector 22 to deflect sufficient water from the 45 splitter to bring the runners back to their normal speed. When desired, the governor may be disconnected and the jet deflector operated by the hand wheel 29. The needle 18 is operated to vary the size of the jet by 50 means of the hand wheel 31.

In the construction shown in Fig. 6, we employ an auxiliary nozzle 32 which operates to relieve the nozzle and pipe line from 55 excessive pressure as the needle 18 is moved to vary the size of the jet. The relief nozzle 32 is provided with a needle 33 for controlling the discharge therefrom. The needle 33 is connected through the medium of the springs 34 and the dash pot 35 with a 60 lever 36 which is pivoted to a stationary fulcrum 37 intermediate between its ends and connected at the other end to the stem of the needle 18. The movement of needle 18 is controlled by variations in the speed of the 65 motor by the governor 23 which operates to

control the flow of fluid under pressure into and out of the opposite sides of cylinder 38, in which is arranged a piston secured to the stem of needle 18. As the speed of the runner increases, due to a lessening of the 70 load, needles 18 and 33 move simultaneously, needle 18 to reduce the size of the jet striking the splitter, and needle 33 to open nozzle 32 to compensate for the closing of nozzle 17. Under the influence of the springs 75 34, the needle 33 is then moved very slowly, due to the dash pot 35, to a closed position.

When the discharge is being automatically controlled by the governor, the link 41, connecting the stem of needle 18 with the hand 80 operating mechanism 42, should be uncoupled. When it is desirable to control the discharge manually, the link 41 is connected as shown and the by-pass valve 43, between the opposite sides of cylinder 38, is opened. 85

We claim:

1. In a hydraulic motor, a rotatable element having an annular series of vanes thereon increasing in height outwardly, a nozzle from which a jet of water issues, and 90 means arranged adjacent the inner edge of the vanes for directing the water onto the vanes.

2. In a hydraulic motor, a pair of axially aligned rotatable elements, each having an annular series of vanes thereon, increasing in height outwardly, a stationary splitter arranged between said elements adapted to divide a jet of water and direct it against the vanes, a nozzle from which the jet of water 100 discharges, and means in the nozzle for varying the size of the jet.

3. In a hydraulic motor, a pair of axially aligned rotatable elements, each having an annular series of vanes thereon, a stationary 105 splitter arranged between said elements adapted to divide a jet of water and direct it against the vanes, and a nozzle from which the jet of water discharges, said vanes increasing in height outwardly from that side 110 of the elements adjacent the splitter.

4. In a hydraulic motor, a pair of axially aligned rotatable elements each having an annular chambers therein increasing in width outwardly, a plurality of vanes arranged in 115 each chamber and a stationary splitter for a jet of water arranged between said chambers.

5. In a jet operated hydraulic motor, a pair of axially aligned rotatable elements, 120 each provided with a plurality of vanes, flaring outwardly to greater width in a plane of the axis of rotation of said motor, a normally stationary splitter for a jet of water arranged between said elements and 125 having overhanging top and bottom edges, a nozzle spaced apart from said splitter, and means in the nozzle for controlling the size of the jet.

6. In a jet operated hydraulic motor, a 130

- normally stationary splitter for the jet of water having a vertical front edge and curved sides, the curvature of the sides varying from the top to the bottom edge.
- 5 7. In a jet operated hydraulic motor, two rotatable elements spaced apart from each other at their outer portions, a plurality of substantially radial vanes arranged on said elements adjacent the circumference thereof,
- 10 said vanes being curved transversely of the plane of rotation at varying curvatures depending upon the distance from the center of rotation, and means arranged between the elements for dividing the jet of water and
- 15 directing the divided portions onto the vanes.
8. In a jet operated hydraulic motor, a shaft, a hub mounted on said shaft, two annular flanges on said hub, an annular member having inwardly and outwardly flaring walls secured to each of said flanges, substantially radial vanes arranged between said walls, and means arranged between said annular members for dividing the jet and directing the divided portions onto said vanes.
- 20 9. A hydraulic motor comprising two rotatable elements each provided with an annular passage extending therethrough, vanes arranged in said passages, a stationary
- 30 splitter for a jet of water arranged between said elements in line with said passages, and a shield arranged between said passages at that portion where the water is not entering or discharging from the passages.
- 35 10. A hydraulic motor comprising two connected rotatable elements spaced apart at their outer portions and having annular passages extending therethrough, vanes arranged in said passages, and stationary circular plates arranged adjacent the intake side of said passages.
- 40 11. A hydraulic motor comprising a normally stationary splitter for a jet of water,
- rotatable elements arranged on opposite sides of said splitter, and a jet deflector for controlling said jet.
12. A hydraulic motor comprising a normally stationary splitter for a jet of water, rotatable elements arranged on opposite sides of said splitter, and a jet deflector operative by variations in speed of said rotating elements for controlling said jet.
13. A hydraulic motor comprising a stationary splitter for a jet of water, rotatable elements arranged on opposite sides of said splitter, a governor connected to said rotating elements and a jet deflector controlled by said governor and for controlling said jet.
14. A hydraulic motor comprising a stationary splitter for a jet of water, runners arranged on opposite sides of said splitter, means for directing a jet of water against said splitter, means operative by the rotation of the runners for controlling said jet and means for varying the size of said jet.
15. In a jet operated hydraulic motor, a normally stationary splitter, rotatable elements arranged on opposite sides of said splitter, said elements including a plurality of vanes flaring outwardly to increased width.
16. In a jet operated hydraulic motor, a normally stationary splitter, rotatable elements arranged on opposite sides of said splitter, said elements including a plurality of vanes flaring outwardly to greater width, the discharge edges of said vanes being curved outwardly.

In testimony whereof, we have hereunto set our hands at San Francisco, California, 80 this 28th day of March, 1913.

WILLIAM A. DOBLE.
LEOPOLD M. KARNASCH.
